UNITED STATES PATENT OFFICE.

AMOS C. STALEY, OF CHICAGO, ILLINOIS.

MULTICOPYING-MACHINE.

No. 871,531.

Specification of Letters Patent.

Patented Nov. 19, 1907.

Application filed May 13, 1907. Serial No. 373,407.

To all whom it may concern:

Be it known that I, AMOS C. STALEY, a citizen of the United States, residing at Chicago, in the county of Cook and State of Illinois, have invented certain new and useful Improvements in Multicopying - Machines, of which the following is a specification.

My invention relates to improvements in multi-copying machines, for producing many copies of a written or printed original.

One of the salient objects of my invention is to provide a machine of the character described, wherein the printing element is a roller coated with a continuous, relatively thick coating of gelatinous composition suitable to receive an ink impression, and to reproduce the same upon a paper sheet pressed in contact therewith.

A further object of my invention is to provide an organized apparatus for rapidly and effectively feeding paper sheets to the printing roller to receive impressions therefrom, and to positively remove the paper sheet from said roller to prevent adherence of the paper thereto.

More specifically an object of my invention is to provide such an apparatus in which printing rollers of different sizes may be used without change in the construction and adjustment of the remaining elements of the machine, and wherein the commencement of any impression will be the same in relation to each paper sheet fed.

Another object of my invention is to provide a construction in which the stripping instrumentalities for removing the paper from the printing roller are carried by a coacting rotary pressure member, serving to maintain the paper in impression-receiving relation to the printing roller, and, further to so arrange said stripping instrumentality that it may coact with the elastic printing rollers of different sizes to automatically properly position such printing roller with respect to the coacting pressure element, the axis of which has a constant position, without damage to the printing roller.

Another object of my invention is to provide an organized apparatus of the character described, of advantageous construction, cheap and easy of manufacture, and reliable, rapid and efficient in operation.

Other and further objects of my invention will become apparent to those skilled in the art from the following description, taken in

conjunction with the accompanying drawings, wherein:

Figure 1 is a side elevation of a machine embodying my invention; Fig. 2 is a section on line 2—2 of Fig. 5. Figs. 3 and 4 are enlarged details. Fig. 5 is a longitudinal section through the machine with the pressure roll in elevation; Fig. 6 is a sectional detail of the pressure roll, and, Fig. 7 is a side elevation thereof.

Throughout the several figures like numerals of reference refer always to like parts.

In the embodiment of my invention I provide a cylindrical roller, which I will herein term the printing roll or roller, having a relatively thick, resilient or elastic coating of gelatinous composition extending continuously over its peripheral surface, an opposing pressure element arranged to coact intermittently with the printing roller to press into contact with the surface of said roller a sheet of paper to receive an impression, the parts being so arranged that the said pressure element coacts with the printing roller throughout the whole, or substantially the whole, of a rotation of the printing roller, and then separates therefrom to relieve the pressure upon the paper and permit restoration of the printing roller to a predetermined initial printing position, there being provided in the machine mechanism for gripping the paper as it is fed in operative relation to the printing roller, stripping the same from the printing roller (to which the paper tends to adhere) and, preferably, means for directing the paper into operative relation to the pressure-element and printing roll, and automatic paper-stop or positioning devices.

In the preferred embodiment of my invention, herein illustrated, I provide a pressure resisting cylinder, having a segmental peripheral surface for contact with the printing roller to drive the latter in rotation, a portion of the pressure resisting cylinder-segment being peripherally open to permit the printing roller to dwell during a portion of the revolution of the said coacting pressure element. The printing roller is preferably yieldingly mounted with respect to the pressure cylinder segment, and is normally positioned so that its periphery intersects the path of rotation of the peripheral portion of said cylinder segment to a greater or less extent dependent upon the diameter of the particular printing roll employed. Prefer-

ably the stripping means for preventing undue adherence of the paper to the printing roll are carried by the cylinder segment and are arranged in such relation to what I may term the "front" edge of the segment—that is the edge which first coacts with the printing roll in producing an impression from the latter—in such arrangement that it operates to move the printing roll to proper position to ride upon the periphery of the cylinder segment. Also I provide in suitable relation to the parts described a feed table, and paper positioning devices movable automatically in proper timed relation to the movements of the gripper.

In the specific embodiment of my invention shown, 10 indicates the frame having suitably journaled therein a shaft 11, rotatable as by means of a handle 12 and carrying the pressure-resisting element indicated as 13, and comprising heads 14 and 14' and a segmental shell 15, said cylinder-segment being preferably hollow and open between the ends of the shell 15. The heads 14 and 14' are preferably also cut away on the chord connecting the ends of the shell 15. Preferably the front end of the shell 15 is depressed as at 16, and the rear end is bent inward as at 17 on a smooth curve. The gripper construction shown comprises a shaft 18 mounted preferably in approximately radial line with the front end of the shell 15, and projecting at both ends beyond the heads of the cylinder, said shaft carrying a curved gripper plate 19 adapted for coaction with the depressed front edge 16 of the shell and arranged when in position shown in Fig. 5 to constitute an inwardly extending eccentric continuation of the shell 15. Slots 20 are cut into the edge of the plate 19, as best shown in Fig. 4. Upon the extremity of shaft 18, projecting beyond head 14' of the cylinder segment, I mount a small crank arm 21 to the extremity of which is secured a spring 22, at its opposite end secured to the head 14' said parts being so arranged that as the gripper plate 19 is moved from open to closed position the crank arm swings past dead center, so that said spring tends to hold the gripper either in closed position in contact with the depressed edge 16 of the segmental shell, or in open position with the crank arm 21 in contact with stop 23 upon the head 14'. Upon the opposite extremity 55 of the gripper shaft 18 I mount an actuating arm 24, provided with a projecting pin 25 adapted for coaction with a suitable cam slot 27 in a stationary cam member 26 secured to the frame. The configuration of the slot 27 is such as to occasion movements of the actuating arm 24, resulting in the opening and closing of the gripper 19 in proper timed relation to the rotation of the cylinder segment.

28 indicates a paper feed board suitably

mounted in the frame at a convenient angle substantially tangent to the peripheral path of rotation of the cylinder segment 13.

29 indicates in general a paper positioning stop, preferably in the form of a light U-bar 70 having its extremities pivoted to the frame members 10 at approximately the level of the lower end of board 28, and extending transversely across the machine in front of the end of said board, said member being provided with depending stop-fingers 30, arranged in register with the slots 20 in the gripper 19. For moving the stop into and out of operative position in suitable timed relation to the action of the gripper 19, I 80 preferably provide upon the member 29 adjacent one of its pivotal points fingers 31 and 32 extending respectively downwardly and upwardly for coaction with two pins 33 and 34 carried by the cylinder member 13 and 85 traveling at different radial distances from the axis of rotation. A spring 35 connected to the member 29 and a frame member 10 and arranged to pass dead center during the movements of the stop member 29, tends to 90 hold the stop in either open or closed position at either extremity of its movement produced by the pins 33 and 34. The relative arrangement of these operating and timing devices is such that during the rotation of 95 the cylinder segment 13, as the front edge of the shell 15 approaches the extremity of the feed board 28 the gripper is opened, and immediately after the said edge of the shell passes the end of the feed board the gripper 100 is closed, both by coaction of pin 24 and cam 25, the paper stop being so arranged that practically simultaneously with the closing of the gripper 19, contact of pin 33 with arm 31 lifts said paper stop to inoperative position where it remains under the influence of spring 35 until about the time when the rear extremity of the shell 15 passes from beneath the feed board 28, when the pin 34 strikes finger 32 of said paper stop, depressing the 110 same and moving the stop to operative position in which the fingers 30 stand projecting downward across the end of the feed board 28.

The printing roller, generally indicated at 40, preferably comprises an interior body 41 115 of wood or the like, having thereon a continuous, uninterrupted relatively thick body or coating of elastic gelatinous compound, of suitable character, indicated at 42, the core 41 being loosely slipped upon a carrying 120 shaft 43 and held against rotation thereon by engagement of a recess 44 in the core with a pin 45, carried by a head 46 fixed to the shaft 43. The shaft 43 is journaled in open bearings at the extremity of carrying arms 48 125 pivoted to the frame, as at 49. Springs 50 normally hold the arms 48 in depressed position in contact with the stop 51 upon the frame, the printing roller 40 under such conditions standing with its periphery intersect- 130

ing the peripheral path of rotation of the shell 15 of the pressure resisting element 13 to a greater or less extent dependent upon the diameter of roll 40. A spring 52 connected with the frame 10 at one end and at its opposite end with the crank arm 53, carried by the shaft 43 of the roll 40, normally holds said printing roll in predetermined position, which I may term its initial printing position.

In operation the handle 12 is rotated to such position that the gripper 19 is opened and the paper stop 29 depressed, a sheet of paper is laid upon the board 28 with its top edge in contact with the stop fingers 30, and the pressure cylinder 13 is rotated, the gripper 19 closing upon the top edge of the paper and the stop member 29 being elevated through the coaction of pin 33 with arm 31. Now the paper, firmly gripped by the gripper 19 is drawn forward, and the eccentric curve of the gripper 19 striking the printing roller 40, the latter lifts its carrying arms against the tension of springs 50 to position the roller 40 to ride upon the periphery of the cylinder segment 13 in contact with the paper sheet, sufficient pressure being constantly maintained by the springs 50 so that a good impression is transferred from the printing roll 40 to the paper. The paper tends firmly to adhere to the printing roll, but is stripped therefrom through the action of the gripper. When the rotation of the cylinder segment brings the rear end of the shell 15 past the edge of the feed board the paper stop is depressed by pin 34 striking and passing the finger 32 of the paper stop, but the gripper is not opened until it reaches nearly the uppermost position in its rotation, so that the paper when freed from the gripper falls far toward the rear of the frame in position easiest for removal of the paper.

Within reasonable limits the size of the roll 40 may be varied to correspond with the length of the sheet to receive the impression, it being the best practice however, to have the printing roll always of somewhat less circumference than the peripheral measurement of shell 15 of the coacting pressure element. The peripheral length of the shell 15 should of course be as great as the maximum length of the paper to be fed to the machine.

It will be observed that during the operation described the eccentric gripper, by reason of its inward curvature, acts as a means to move the printing roll to proper operating position for coaction with the shell of the pressure cylinder, the comparative springiness or elasticity of the thick gelatinous coating of the printing roll permitting it to receive the slight impact of the gripper without damage and without noise.

It will be apparent that whenever the parts come to such position that the open

portion of the cylinder 13 is presented to the printing roll, the springs 50 return the carrying arms and the roll to idle position, while the spring 52 rotates the printing roll upon its axis to initial printing position. 70

It will be apparent that the construction of the machine may be varied in many respects without departure from the spirit and scope of my invention, and while I have for purposes of full disclosure herein specifically 75 shown and described a particular embodiment of my machine, it will be understood that I do not intend to limit my invention thereto in its broader aspects.

Having thus described my invention, what 80 I claim and desire to secure by Letters Patent, of the United States, is:

1. In a multi-copy machine, a cylinder-segment, a printing roller arranged to be frictionally driven thereby, provided with 85 a continuous coating of gelatinous composition, means for yieldingly holding said printing roller in position to intersect the peripheral path of said cylinder segment and means for returning the printing roller to 90 invariable position when freed by the cylinder-segment.

2. In a multi-copy machine, a rotatable printing roller comprising a core and a relatively thick coating of elastic gelatinous 95 composition, a rotatable pressure element intermittently coacting therewith to frictionally drive said roller, means for maintaining a pressure between the said coacting elements yielding to permit bodily repression 100 of the printing roller, and means for restoring the printing roller to invariable position when intermittently freed by the coacting pressure element.

3. In a multicopy machine, the combination of a frame, a cylinder segment mounted for rotation therein, means for rotating said segment, a printing roller provided with a peripheral coating of elastic gelatinous composition, bearing members for said roller 110 yieldingly mounted on the frame to normally position the printing roller to intersect peripherally the path of the cylinder segment, means for directing paper between the cylinder segment and printing roller, 115 and paper gripping means carried by said segment.

4. In a multi-copy machine, a driving cylinder segment, a coöperating printing roller, provided with a thick peripheral body of 120 elastic gelatinous composition, yieldingly positioned to intersect peripherally the path of the cylinder segment, and a gripper carried by the segment arranged when closed to extend inwardly in the segment from an 125 edge of its periphery, for coaction with the printing roller to move it to operative position.

5. In a multi-copy machine, a printing roller having an elastic peripheral coating of 130

gelatinous composition, a yielding support for said roller, wherein said roller is removably mounted, and a pressure-resisting element intermittently coacting with said printing roller to drive the same, providing a segmental surface for frictionally driving the printing roller.

6. In a multicopy machine, a frame, a printing roller yieldingly supported with respect to the frame, provided with a coating of elastic gelatinous composition; a rotatable cylinder segment mounted in the frame for coaction with the printing roller to drive the latter; means for driving said cylinder

segment in rotation; means for directing paper between the cylinder segment and printing roller, paper gripping means carried by the cylinder segment arranged to move the printing roller to printing position, and means for timing the operations of the gripper carried by the frame.

In testimony whereof I hereunto set my hand in the presence of two witnesses.

AMOS C. STALEY.

In the presence of—

FORÉE BAIN,
MARY F. ALLEN.
